Primary Examiner — T Chase Nelson*Assistant Examiner* — Jonathan J. Han(74) *Attorney, Agent, or Firm* — Dunlap Bennett & Ludwig PLLC(57) **CLAIM**

The ornamental design for a wrist rest, as shown and described.

DESCRIPTION

FIG. 1 is a top rear perspective view of a wrist rest, showing my new design;

FIG. 2 is a rear elevation view thereof;

FIG. 3 is a front elevation view thereof;

FIG. 4 is a right elevation view thereof, the left elevation view being a mirror image thereof; and,

FIG. 5 is a top plan view thereof.

The broken lines shown in the drawings depict portions of the wrist rest that form no part of the claimed design.

1 Claim, 4 Drawing Sheets(56)
